UNITED STATES PATENT OFFICE.

DAVID RENSHAW, OF COHASSET, MASSACHUSETTS.

SECTIONAL STEAM-GENERATOR.

SPECIFICATION forming part of Letters Patent No. 230,818, dated August 3, 1880.

Application filed January 14, 1880.

To all whom it may concern :

Be it known that I, DAVID RENSHAW, of the town of Cohasset, in the county of Norfolk and State of Massachusetts, have invented certain Improvements in Sectional Steam-Generators, which improvements are fully described in the following specification and accompanying drawings.

My invention consists in an improved sectional steam generator so constructed that the sections will set above the fire; or, if requisite, some of them may be placed beyond the fire, and the heated gases passed through such generators or sections. This is especially for house-heating purposes, though it may well be applied for power; and one of its features consists in the fact that all the joints are securely protected from the direct heat of the fire; and another feature is that a perfect circulation of the water is secured.

Each section is constructed with a pipe running somewhat in the form of a parallelogram, and having curved pipes D, leading from the lower portion, A, to the side portions, C, and top portion, B, as shown, the pipes being curved at their bends to admit of a free circulation of water. This construction exposes the small quantity of water in the lower pipe to the direct heat of the fire, and allows the heated gases to pass up between the sections and come in contact with the other portions of the sections; and it affords a large upper water body from which the steam can be evaporated while the water is being rapidly circulated.

In the drawings, Figure 1 shows a front view

of one section arranged over the fire-box, and Fig. 2 shows a side elevation of the same.

A represents the lower pipe of the section; B, the upper pipe; C C, the side pipes; and D D, pipes curved to admit of expansion and contraction and circulation, connecting the pipes A with the pipes B and C.

E is a pipe emerging from one side of the pipe A, and fitted with flanges, so that all of the pipes A may be bolted together at their lower parts and the pipe E will serve to feed and to blow off the sections.

G is a steam-pipe or drum, flanged in the ordinary way to bolt the upper portions of the sections together, and arranged to take the steam from each section and pass it to its work.

Having thus described my invention, what I claim as new, and desire to secure by Letters Patent, is—

A steam-generator composed of sections, each section consisting of a continuous pipe, A, B, and C C, the lower portion, A, being small and horizontal, the side portions, C C, being vertical and tapering, and the upper portion, B, large and horizontal, said pipe being curved at its bends and having curved pipes D D, connecting the part A with the parts B and C; said sections being connected together by flanges upon the steam-drum G and feed-pipe E, all substantially as described.

DAVID RENSHAW.
